UNITED STATES PATENT OFFICE.

WILLIAM FAULHABER, OF KENOSHA, WISCONSIN.

WINDOW CONSTRUCTION.

1,119,587.

Specification of Letters Patent.

Patented Dec. 1, 1914.

Application filed March 25, 1914. Serial No. 827,062.

To all whom it may concern:

Be it known that I, WILLIAM FAULHABER, a citizen of the United States, and a resident of the city of Kenosha, county of Kenosha, 5 and State of Wisconsin, have invented certain new and useful Improvements in Window Construction, of which the following is a specification.

My invention relates to improvements in 10 window constructions and has for its object an improved construction of this character equipped with an improved form of storm sash and window and constructed to facilitate ventilation and also locking of 15 the window.

The invention consists in the combinations and arrangements of parts hereinafter described and claimed.

The invention will be best understood by 20 reference to the accompanying drawings forming a part of this specification, and in which—

Figure 1 is an inner perspective view of 25 a window construction embodying my invention, Fig. 2, a perspective view of the lower portion of the storm sash employed in the construction, Fig. 3, a vertical section taken through the window construction, and Fig. 4, a section similar to Fig. 3, but showing 30 the parts in different positions.

The preferred form of construction as 35 illustrated in the drawings comprises an upper sash 5 and a lower sash 6 slidably mounted in the window frame in the usual manner. An outer storm sash 7 is hinged at its upper end 8 in the window frame and is adapted to close the outer side of the frame as indicated in Fig. 3. Sash 7 is connected 40 at its lower end by means of links 9 with the lower rail 10 of the upper sash 5, so that when said upper sash is lowered, the lower portion of the storm sash 7 will be swung outwardly and vice-versa to permit of proper ventilation.

The upper portion of sash 5 is connected 45 by a link 11 with a lever 12 which is pivoted to a plate 13 secured to the inner side of the window frame just above the lower sash 6. By this arrangement it will be observed 50 that sashes 6 and 7 may be readily manipulated by means of lever 12. Lever 12 also carries a link 14 having an angularly turned

end 15 adapted to engage different perforations 16 in an angular plate 17 secured to the upper portion of the lower sash 6. By 55 this arrangement when link 14 is engaged with the uppermost perforation in plate 17 the sashes will be positively locked against opening from the outside. When link 14 is engaged with one of the lower perforations 60 in plate 17 as indicated in Fig. 4, sashes 5 and 6 will be caused to move in unison with each other and with sash 7 so as to regulate the ventilation as desired.

While I have illustrated and described 65 the preferred form of construction for carrying my invention into effect, this is capable of variation and modification without departing from the spirit of the invention. I, therefore, do not wish to be limited 70 to the precise details of construction set forth, but desire to avail myself of such variations and modifications as come within the scope of the appended claims.

Having described my invention what I 75 claim as new and desire to secure by Letters Patent is:

1. A window construction comprising a frame and upper and lower sashes slidable therein; a storm sash hinged at its upper 80 end in said frame and extending the full length of the window; and an operative connection between the lower rail of said upper sash and the lower portion of said storm sash, whereby lowering of said upper sash 85 swings the lower end of said storm sash outwardly, substantially as described.

2. A window construction comprising a frame and upper and lower sashes slidable therein; a storm sash hinged at its upper 90 end in said frame and extending the full length of the window; and a link connection between the lower rail of said upper sash and the lower portion of said storm sash, whereby lowering of said upper sash swings 95 the lower end of said storm sash outwardly, substantially as described.

In testimony whereof I have signed my name to this specification in the presence of two subscribing witnesses.

WILLIAM FAULHABER.
